UNITED STATES PATENT OFFICE.

ERNEST H. PEABODY, OF NEW YORK, N. Y., ASSIGNEE TO THE BABCOCK & WILCOX COMPANY, OF BATONNE, NEW JERSEY, A CORPORATION OF NEW JERSEY.

APPARATUS FOR BURNING FINELY-DIVIDED FUEL.

1,124,654.

Specification of Letters Patent. Patented Jan. 26, 1915.

Application filed July 22, 1911. Serial No. 661,367.

To all whom it may concern:

Be it known that I, ERNEST H. PEABODY, a citizen of the United States, residing at the city of New York, borough of Manhattan, county of New York, State of New York, have invented certain new and useful Improvements in Apparatus for Burning Finely-Divided Fuel, of which the following is a specification:

My invention relates to an air deflecting plate for use in connection with a burner for finely-divided fuel for giving the air for combustion a whirling or rotating motion. In the form shown by me the plate is given a conical form and it will be understood by reference to the accompanying drawings in which—

Figure 1 is a front elevation of one form of an air deflecting plate according to the present invention; Fig. 2 a top view thereof; and Fig. 3 a detail view of the blades.

Similar reference numerals indicate similar parts in the several views.

Referring to the drawings, the numeral 1 designates a base, having a circular opening therein, which is adapted to be secured to the furnace wall in any convenient manner.

2 is a central ring, and between plate 1 and the opening thereof and the ring 2 I place a series of deflecting blades 3. In the preferred form of construction these blades are stamped from a flat sheet metal plate 4 and bent upwardly about 45 degrees to the plane of the plate. The ends of the plate 4 are then brought together and riveted, or otherwise secured along the line 5 to form a frustum of a cone. In stamping the blades 3 I leave marginal edges for the purpose of securing the cone to the base 1 and ring 2, and for this purpose the base of the cone is flattened out at 6 to provide a convenient means of attachment to the base 1. The burner 7 terminates in proximity to the central opening of ring 2, either immediately in front, or at the rear, or within said opening. The disposition of the deflecting plate relatively to the furnace may be reversed from that shown in Fig. 2, that is, it may be secured to the furnace at its smaller end instead of at its wider end.

The prime object of all methods of burning finely-divided fuel is to obtain a continuous and intimate mixture of the fuel and an amount of air as nearly as possible

equal to the theoretical quantity required to effect complete combustion. If the mixing process is not uniform and continuous, an intermittent explosive action takes place, resulting in severe vibrations in the furnace. If the mixture is not thoroughly effected a large excess of air is required with resultant loss in efficiency. By the use of the herein described deflecting plate I aim to secure a continuous, uniform and intimate mixture by causing the volume or current of air which is being drawn or forced into the combustion chamber to come in contact with the blades so placed as to deflect the air in planes at an angle to its direction of travel to thereby impart to the air a whirling or rotating motion in a path surrounding, cutting through and mixing with the stream of finely-divided fuel. This action imparts to the fuel, as a consequence, a whirling or rotating motion in the same direction as that assumed by the air, and, in so doing, thoroughly mixes the air with the fuel, thereby making a solid flame. The resulting turning over and over of the fuel in a gradually expanding spray brings all of its particles into contact with the oxygen of the air, and this insures complete combustion. The currents of air through the deflecting plate may be induced by the stack draft or by a forced draft. As the inner ends of the blades terminate in close proximity to the burner the whirling motion begins immediately after the air passes through the deflecting plate, so that the fuel is intermixed with and surrounded by the whirling volume of air practically immediately after it is ejected from the burner.

In the form shown, the blades 3 are at substantially an angle of 45 degrees to the surface of the cone, and the cone itself substantially 45 degrees to the base 1.

What I claim and desire to secure by Letters Patent of the United States is:—

1. The combination with a burner of an air deflecting device in the form of a frustum of a cone having a restricted opening at the smaller end thereof, a plurality of blades spaced apart to provide apertures for the admission of air and inclined to the surface of the cone, said blades converging toward said one end thereof terminating adjacent said opening, and said burner terminating in proximity to said opening.

2. The combination with a burner of an air deflecting device in the form of a frustum of a cone having a restricted opening at the smaller end thereof, a plurality of 5 blades spaced apart to provide apertures for the admission of air and inclined approximately 45° to the surface of the cone, said blades converging toward and one end thereof terminating adjacent said opening, 10 and said burner terminating in proximity to said opening.

3. The combination with a burner of an air deflecting device in the form of a frustum of a cone having a restricted opening at 15 the smaller end thereof, the surface of said cone inclined approximately 45° to the

plane of the base and having a plurality of blades spaced apart to provide apertures for the admission of air and inclined to the surface of the cone, said blades converging 20 toward and having one end thereof terminating adjacent said opening, and said burner terminating in proximity to said opening.

In testimony whereof I have hereunto 25 signed my name in the presence of two subscribing witnesses.

ERNEST H. PEABODY.
